SHOULDER PAD

Filed May 2, 1946

UNITED STATES PATENT OFFICE

2,424,662

SHOULDER PAD

Max Lavin, Philadelphia, Pa.

Application May 2, 1946, Serial No. 666,765

1 Claim. (Cl. 2-268)

1

The present invention relates to shoulder pads, and has for its general object to provide a pad which will give the shoulders of the garment the desired more or less square-ended shape, shall lodge comfortably on wearer's shoulder and shall withstand wear throughout the life of the garment and preserve its quality of shaping the shoulders of the garment as desired and intended.

Another object of the present invention is to provide a shoulder pad of the type described, which curves downwardly in front and back and which while having a curved and squared outer end, its other edges are thinned or feathered. With this construction the shoulder pad fits snugly over the wearer's shoulder, performs its function of shaping the shoulder of the garment and does not interfere with the lines of the garment or the draping of the material of the garment over the shoulder.

Other objects and advantages of the present invention will be apparent to persons skilled in the art from the following specification and accompanying drawings which illustrate a preferred embodiment of the present invention.

In the drawings:

Figure 1 is a perspective view of the shoulder pad;

Figure 2 is an end view of Figure 1;

Figure 3 is a partial sectional view on line 3-3 in Figure 1;

Figure 4 is a partial sectional view taken on line 4-4 of Figure 3;

Figure 5 is a plan view of the cotton or wadding assembly before it is enclosed in the outer casing or envelope;

Figure 6 is a plan view of the outer casing or envelope;

Figure 7 is an end view of Figure 5.

Referring particularly to Figures 1 and 2 of the drawings, it will be seen that the shoulder pad of the present invention is roughly triangular in shape and is provided with a transversely extending arched or crescent shaped end panel 10, which is best illustrated in Figure 2. This transversely arched panel will be seen as conforming to the shoulder of the wearer illustrated by dot and dash line 11 in that it curves down on the front and back of the shoulder, these front and back edges 12 and 13 being thinned or feathered with their rear ends meeting at a common point 14, as best shown in Figure 1. Thus, the present shoulder pad with its maximum thickness along the vertical median line of the crescent shaped end panel 10 tapers off to 14 along the length of

2

the shoulder and also tapers off transversely in opposite directions toward the edges 12 and 13 of the pad.

The outer envelope or casing of the shoulder pad includes the crescent shaped end panel 10, which is of a suitable textile fabric layer reenforced to maintain the shape shown in Figure 2 by two layers 15 of buckram or similar stiffening material. The upper panel 16 of the outer casing or envelope is also provided with two layers of buckram 17 and is stitched to the upper edge of the end panel 10 by the line of stitching 18. The bottom panel 19 of the casing preferably consists of a single layer of casing material, not reinforced by any buckram, similarly stitched to the bottom edge of the end panel 10 by the line of stitching 20. After the previously prepared filler, which will be described later, has been placed between the panels 16 and 19 of the casing, these parts are stitched together along the lines 21 and 22 thereby forming the thin edges 12 and 13 and completely enveloping the filler within the casing.

What has been described to this point is the outer envelope or casing which comprises the upper triangular layer of textile material 16 reinforced by two layers of buckram, the lower triangular non-reinforced fabric 19, and the crescent shaped reinforced end panel 10.

In addition to this outer envelope or casing, the present shoulder pad comprises an inner open-ended envelope or casing containing a filling of wadding or cotton 23.

This inner envelope comprises a triangular top layer 33 of buckram or similar suitable stiffening material and a correspondingly shaped bottom layer 34 of relatively soft and flexible material. In the preferred form, this bottom layer 34 is of a high quality sheeted wadding, which is available on the market in the form of a layer 32 of lightly and loosely felted cotton wadding or the like disposed between two layers 30, 31 of thin cotton sheeting. The layers 33 and 34 are stitched together along the line 35 and 36 to provide marginal edges 37.

The filling 23 of any suitable cotton wadding is shaped to fill the inner envelope and for this purpose it is generally of triangular shape with its greatest thickness in the median portion of the base of the triangle, the filling being further characterized in that it tapers off in thickness toward its opposite side edges as well as towards the apex of the triangle.

In the present construction, the filling 23 is inserted into the inner envelope through its open

end thereof, this end of the envelope being left open as is seen in Figures 3, 5 and 7. With the filling 23 in the inner envelope, the same is ready for assembly within the outer envelope.

As shown in Figure 6, the outer envelope, which is adapted to receive the inner envelope and filling 23, has its top panel 16 stitched to the buckram 17 by the median line of stitching 40. Similarly, the end panel 10 is stitched to its buckram reenforcement by a median line of stitching 41. In addition, as previously described, the top and bottom panels 16 and 19 are respectively secured to the upper and lower edges of the end panel 10 by the lines of stitching 18 and 20. The inner envelope with its filling 23 is received between the top and bottom panels of the outer envelope, with its open base and perhaps some of the protruding filler 23, as shown in Figure 5, disposed against the base 10. The assembly is now finished by the lines of stitching 21 and 22, which unite the overlying marginal edges of the outer and inner envelopes.

The crescent-shaped reenforced base or end of the outer envelope lends the shoulder pad the desired sharply defined squared end, the attainment of this objective being augmented by the open-ended construction of the inner envelope containing the filling material or padding 23. For it is this open-ended construction that permits the cotton filling or padding 23 to resiliently press against the crescent shaped reenforced end panel 10 of the outer envelope. Thus, the open based inner envelope cooperates with the reenforced base of the outer envelope to produce the square end and to maintain the square end through the life of the garment.

It will be understood, of course, that the present invention is susceptible of various changes and modifications which may be made from time to time without departing from the real spirit or general principles of the present invention, and accordingly it is intended to claim the same

broadly as well as specifically as indicated in the appended claim.

What is claimed as new and useful is:

A shoulder pad for garments comprising an open-ended envelope of generally triangular shape in perimetral outline, the opposite side edges of which converge from the open end of the envelope toward the apex thereof, said envelope being internally filled with a filling wadding of gradually decreasing depth or thickness laterally to either side of the median vertical plane of the envelope, the filled envelope being arched transversely of said median plane with the filling wadding thereof terminating flush with the open-end of the envelope whereby the exposed surface of the wadding is of substantially crescent shape in outline and lies in a substantially flat plane extending transversely of said median plane and substantially normal to the common plane of the converging side edges of the filled envelope, and a stiffened closure for said open-end of the envelope adapted to overlie the crescent-shaped flat surface of the filling wadding, said closure being of crescent shape in outline and being secured along its marginal edges to the edges of the envelope which define the open end thereof, said end closure imparting to the shoulder pad a sharply defined squared end.
